UNITED STATES PATENT OFFICE.

ALBERT HAAS, OF NEW YORK, N. Y.

WATER-ELEVATOR.

No. 904,951.

Specification of Letters Patent.

Patented Nov. 24, 1903.

Application filed January 3, 1903. Serial No. 402,369.

To all whom it may concern:

Be it known that I, ALBERT HAAS, a citizen of the United States, and a resident of the city of New York, borough of Manhattan, in the county and State of New York, have invented a new and useful Improvement in Water-Elevators, of which the following is a full, clear, and exact description.

The purpose of the invention is to improve upon a construction for water or liquid elevators, for which Letters Patent were granted to me October 22, 1907, No. 868,657, so as to adapt the same to various conditions and circumstances under which it has been found that a double spiral screw can be successfully employed, the said improvements relating particularly to the construction of the body of the device and the aforesaid double spiral screw, and the details of construction at the receiving and discharge portions of the device.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a longitudinal section through the entire device; Fig. 2 is an enlarged transverse section taken practically on the line 2—2 of Fig. 1; Fig. 3 is an enlarged transverse section taken substantially on the line 3—3 of Fig. 1; Fig. 4 is an enlarged transverse section taken practically on the line 4—4 of Fig. 1; Fig. 5 is a side elevation of a portion of the body shown in Fig. 1; Fig. 6 is an exterior view of a portion of a modified form of the body; Fig. 7 is an enlarged section through the type of body shown in Fig. 6; Figs. 8 and 9 are vertical sections through a further modified form of the body; Fig. 10 is a side elevation of the type of body in which a double spiral screw forms an integral portion of the cylinder, and wherein said cylinder and the said screw are made in longitudinal sections; Fig. 11 is a transverse section taken practically on the line 11—11 of Fig. 10; Fig. 12 is a vertical section through a member of the cylinder when the cylinder is constructed in a series of members to be placed one on top of the other, and wherein each member contains a complete section of a double spiral screw; and Fig. 13

is a plan view of the form of the cylinder illustrated in Fig. 12.

A represents a tank or a receptacle of any desired size and of any suitable formation. 30 This receptacle is preferably closed except at one end where a chute 10 is located for the discharge of liquid. A suitable bearing 11 is located at the top central portion of the receptacle A, and a drive shaft 12 is mounted 65 to turn in the said bearing 11, and the said drive shaft 12 is provided with a suitable driving pulley 14 connected by a belt 14^a with any source of power, but the connection between said source of power and said shaft 70 may be varied if desired.

A cylinder or tubular body B extends up through the bottom of the receptacle A, passing through the said bottom in a liquid-tight manner, and the said cylinder or tubular body B may be of any desired length and extends down into the container of the liquid or water to be elevated. The said cylinder or tubular body B is provided within the receptacle with an annular flange 13 secured 80 thereto in any approved manner, and is provided at its lower end with a similar flange 13^a. The upper flange 13 is made to engage with a ring-like flange 15 that rests upon it, and a yoke 16 extends upward from the central portion of the said ring-like flange 15, as is best shown in Fig. 2, and from the central under portion of the yoke 13, a conical projection 17 is carried downward, as is illustrated in Fig. 1. The yoke permits the water that is raised in the cylinder B in a manner to be hereinafter described, to pass freely into the receptacle A, and the conical projection 17 serves to deflect the entering current of water so as to make the flow from the cylinder to the receptacle A more uniform. 95

Shields 18 extend from the opposite sides of the yoke 13, and these shields are given a downward inclination to a certain extent, as is illustrated in Figs. 1 and 2, and a short 100 spindle 19 is carried up from the central portion of the yoke 16, and this spindle 19 is attached to the drive shaft 12 in any suitable manner. The flange 15 supporting the yoke 16 is secured to the upper flange 13 on the cylinder B by bolts 20, or the equivalents of the same, and the side members of the yoke 16 are more or less sharpened at opposite diagonal points, as is shown in Fig. 3, so that as the cylinder B is rotated, the yoke 16 will 105 cut through the water in the receptacle A 110 offering the least possible amount of resist-

ance thereto. A flange 22 is made to engage with the flange 13^a at the bottom of the said cylinder B, and this flange 22 is of ring-like construction corresponding to the flange 15 at the top, and from the flange 22 a yoke 24 extends downward, and the two flanges 22 and 13^a are connected by bolts 23, or their equivalents. A spindle 25 is made integral with or is attached to the lower central portion of the lower yoke 24, and this spindle 25 is adapted to turn in a suitable bearing 26 located at the bottom of the container of the liquid, or at any desired point between the top and the bottom of said container.

15 A double spiral screw C is located within the cylinder or tubular body B, being adapted to turn therewith. This screw extends up to the upper end portion of the cylinder or tubular body B, and to the bottom portion thereof, the said cylinder being open at its top and at its bottom, and at the lower end of the screw C a spindle 27 is secured, and this spindle has bearing in the bottom portion of the yoke 24, and serves as the principal support for the said double spiral screw C in the said cylinder, as is clearly shown in Fig. 1. The side members of the lower yoke 24 have their diagonal opposite edges sharpened to a greater or lesser degree, as is shown at 28 in Fig. 4, so that as the cylinder B revolves the said yoke 24 will offer but little resistance to the water that is drawn up by the screw C.

The cylinder or tubular body B and the spiral screw C are usually constructed in one or more sections, the sections of the cylinder being of corresponding length to those of the screw, and the double spiral screw C may be given any desired pitch. The cylinder B is provided with an interior spiral support for 40 the edges of the double spiral screw, which support also acts in the capacity of a guide and is auxiliary to the aforesaid lower support 27. This interior spiral support may be constructed in different ways, accomplishing 45 the same result.

In the construction of the cylinder B shown in Figs. 1 and 5, an internal double groove 29 is produced corresponding to the pitch of the screw C, the said groove receiving the edge of the said screw, and the said groove may be formed by a chuck, or cast in the cylinder, or be produced by any other process in such manner that there shall be a corresponding spiral bead on the outside of 55 the cylinder or tubular body, thus producing practically an even thickness of material and avoiding any weakening of the cylinder or tubular body B along the line of the groove. The cylinder or tubular body B 60 may also be constructed as shown in Figs. 6 and 7, wherein the cylinder in one piece, or in sections, is constructed of two strips 31 and 32 of sheet metal, or other suitable material, carried spirally around a common 65 center so as to form the required cylindrical

body, the lower edge 33 always overlapping the upper edge 34 of the other strip in such manner that the upper edge is always on the inside of the cylinder or tubular body B, thereby forming a shoulder upon and 70 against which the edges of the double spiral screw C rest, the double spiral screw C being of the same pitch as the said continuous shoulders formed within the cylinder. The overlapping edges of the strips 31 and 32 75 forming the cylinder B are secured together by rivets 35, but they may be welded or connected in any suitable manner.

A guide and support for the double spiral screw C may also be provided in the manner 80 shown in Fig. 9, wherein two continuous spiral ribs 36 and 36^a are either attached to or are integral with the inner face of the said tubular body, which ribs may be rectangular, triangular, or may be given any other cross sectional shape.

As shown, when the cylinder or tubular body B is of sufficient thickness, as for example in small structures, two continuous spiral grooves 37 and 37^a may be interiorly produced, the interior of the cylinder remaining plain, as illustrated in Fig. 8. In each of the constructions above referred to, the double spiral screw fits fairly close into the grooves, or upon the shoulders or offsets 92 produced in the interior of the cylinder, and the screw is placed in position by being introduced at one end of the cylinder and then driven in after the manner of an ordinary screw.

Apart from the combination of the double spiral screw and the cylinder or tubular body above described, the method of connecting the screw and the cylinder in closing it may be still further varied, as in the construction of water or liquid elevators of such large dimensions as may be required for extensive water works, drainage and irrigation works, etc. Thus the cylinder designated as A' in Figs. 10 and 11, may be made in two sections 38, and the double spiral screw therefor designated as C' is also in two sections 39 integral with the corresponding sections of the cylinder. In completing such a body portion of the elevator, the sections are brought together and are secured by bolts or their equivalents, passed through apertured lugs constituting integral portions of the cylinder, and each section is provided with plain, ribbed, or rounded 115 surfaces 40 and correspondingly grooved surfaces 41, shown in Figs. 10 and 11, which in assembling the sections come to a rest against the edge of an opposing section and thus fit to or into them, the projections from one section entering the grooves in the other section.

The sections just described, and the sections shown in Figs. 12 and 13, can be readily made of iron, steel, or other metal. In Figs. 130

12 and 13, the cylinder B² is constructed in longitudinal complete sections 42, that is the sections are complete in cross section, and the double spiral screw C² is in corresponding sections 43 and they constitute integral portions of the cylinder sections 42. In assembling the complete sections shown in Figs. 12 and 13, they are connected by passing bolts or their equivalents through apertured lugs 44 at their end portions, and at one end of each of said sections, a rib 45, or its equivalent, is formed, and a corresponding recess 46 is formed at the opposite end of the section.

15 I desire it to be understood that I do not confine myself to any particular method of connecting the parts of the cylinder and the screw when made in integral sections. Particularly in the construction shown in Figs. 10, 11, 12 and 13, a single spiral may be employed instead of the double spiral shown, as also perhaps in some other special cases. I also desire it to be understood that a single spiral may be employed, the same to be continuous from bottom to top--more or less--of the cylinder, in which event a single spiral groove, shoulder, offset or rib is provided in the interior of the cylinder, or such support for the spiral, in most cases, may be omitted; and in such an event the lower end of the single spiral is fastened, supported or attached at the lower end of the cylinder in any approved manner; that is, when the sections of the screw are not integral with sections of the cylinder.

Having thus described my invention, I claim as new and desire to secure by Letters Patent:

1. In an elevator for water and other liquid, a cylinder, a support in which the cylinder is mounted to rotate, a spiral elevating device within and turning with the cylinder, and guides for the spiral elevating device also located within the cylinder, corresponding to the pitch thereof and engaging its edges.

2. In an elevator for water and other liquid, a cylinder, a support in which the cylinder is mounted to revolve, a water elevating device of spiral formation located within

and turning with the cylinder, and a guide for the spiral and forming a portion of the inner wall of the cylinder, which guide conforms to the pitch of the spiral and engages its edges.

55

3. In an elevator for water and other liquid, a cylinder provided with an inlet and an outlet, a support in which the cylinder is mounted to revolve, and a water elevating device consisting of a double spiral screw 60 located within and turning with the cylinder and having double spiral grooves constituting a portion of the inner wall of the cylinder, which grooves have the same pitch as the double spiral screw and receive the edges 65 thereof.

4. In an elevator for water and other fluid, a cylinder, a double spiral screw located within the said cylinder and means for forcing the said screw to turn with the cylinder, 70 yoke bearings for the cylinder at the top and at the bottom, said portions of the cylinder being open, bearings for the said yokes, a conical projection from the upper yoke, and hoods extending from opposite sides of 75 the said yoke over the upper edge of the cylinder at a distance therefrom.

5. In an elevator for water and other fluid, a cylinder, a double spiral screw located within the said cylinder and means for forcing the said screw to turn with the cylinder, yoke bearings for the cylinder at the top and at the bottom, said portions of the cylinder being open, bearings for the said yokes, a conical projection from the upper yoke, and 80 hoods extending from opposite sides of the said yoke over the upper edge of the cylinder at a distance therefrom, each of the said yokes being provided at opposite edges of its side members with beveled surfaces whereby 85 to readily cut through the water or liquid as the cylinder is revolved.

In testimony whereof I have signed my name to this specification in the presence of two subscribing witnesses.

ALBERT HAAS.
